UNITED STATES PATENT OFFICE.

CLARENCE B. KLOPFENSTINE, OF DES MOINES, IOWA, ASSIGNOR TO IOWA CORD TIRE COMPANY, OF DES MOINES, IOWA, A CORPORATION OF IOWA.

DESIGN FOR A NON-SKID TIRE.

53,372.

Specification for Design.

Patented May 27, 1919.

Application filed March 6, 1919. Serial No. 281,101. Term of patent 14 years.

To all whom it may concern:

Be it known that I, CLARENCE B. KLOPFENSTINE, a citizen of the United States, residing at Des Moines, in the county of Polk and State of Iowa, have invented a new, original, and ornamental Design for a Non-Skid Tire, of which the following is a specification, reference being had therein to the accompanying drawings.

The figure is a perspective view of a complete tire, showing my new design.

I claim:

The ornamental design for a non-skid tire, as shown.

In testimony whereof I hereunto affix my signature.

CLARENCE B. KLOPFENSTINE.
